UNITED STATES PATENT OFFICE.

CLAUDE SPICER, OF ELYRIA, OHIO.

MECHANISM FOR CONTROLLING AIR AND SAND ON CARS.

No. 897,229

Specification of Letters Patent.

Patented Aug. 25, 1908.

Application filed April 13, 1908. Serial No. 426,687.

To all whom it may concern:

Be it known that I, CLAUDE SPICER, a citizen of the United States, residing at Elyria, in the county of Lorain and State of Ohio, have invented certain new and useful Improvements in Mechanism for Controlling Air and Sand on Cars, and do declare that the following is a full, clear, and exact description of the invention, which will enable others skilled in the art to which it appertains to make and use the same.

My invention relates to mechanism for controlling air and sand on cars, and the invention consists in a combination handle which is adapted to control both the flow of air to the brakes and the flow of sand to the wheels to prevent slipping, all substantially as shown and described and particularly pointed out in the claims.

20 In the accompanying drawings, Figure 1 is a perspective view of my invention, and Fig. 2 is a sectional elevation thereof shown with associated parts in full lines, as hereinafter fully described.

25 The design or purpose of the invention as thus disclosed is to utilize one handle for two purposes, and which will enable a motor man to operate both the air brake and the sanding mechanism with one and the same hand and 30 at the same time or successively as he may please, while he has his grip on the electrical controller or crank with the other hand, not shown.

35 The invention is, therefore, comprised essentially in the handle H as a whole, and which consists in or of several parts comprising a head h having a tubular hub h' adapted to engage upon the end of valve controlling stem or shaft S and rotate the same to open 40 the rotatable valve V at the bottom thereof in the coupling C and of a crank shaped member B, having a sleeve 2 engaged upon a post 3 on head h, and an arm 4 at right angles to said sleeve adapted to engage stem 5 of the 45 lift valve above the same in the coupling C'. Presumably air is used in this latter connection to feed the sand and controlled by valve V' therein having said stem 5. Now, having the two valves V and V' relatively arranged 50 as shown, and one rotatable and the other adapted to be lifted, and with the handle H constructed and operatively equipped as shown, the two valves are controllable for either or both purposes by a single hand of the operator. This is accomplished by mov-

ing handle H to either right or left as may be provided to operate the brake, and by rotating sleeve handle grip 8 on the stem 9 of said handle to operate the sanding mechanism or valve. Said sleeve 8 has a right angled projection 10 at its inner end provided with a substantially V shaped depression or recess 12 in its top engaging a roller 13 on the sleeve 2. It follows when sleeve 8 is axially rotated on stem 9 that the projection 10 is rocked in respect to roller 13, in which case the said roller is caused to run up one side or the other of the depression or double cam 12 and raise sleeve 2 on its post 3 correspondingly. This lifts arm 4 and raises valve V 70 through its stem 5, thus opening the sanding channel as planned for. Pipe connections P and P' respectively are made with the respective valve couplings, C and C'.

Sleeve 2 should be splined or otherwise held in rotary engagement with post 3 but adapted to slide thereon within limits. Handle stem 9 is threaded into head h and all the foregoing parts are separable or knock-down. The handle is further provided with a cap 15 at or on its outer end and which is shown as extending inward far enough to make a definite grip for the handle when it is ordinarily operated for braking alone, while the sleeve 8 is shown as fluted or with a roughened surface so as to afford a more ready hold or grip when it is to be rotated and sanding is to be done.

As shown the entire handle structure is supported on stem or shaft S as a fixed member though rotatable, and with which the head h is rigid, and the valves V and V' are arranged axially one over the other. The several parts comprising head h, and the parts 8, 9 and 15 are understood as being included in the handle proper. As to the said valves V and V' they might possibly be exchanged as to function and the lower one be used for sanding and the upper for air brake, but this would not affect the scope and purpose of the invention.

The handle proper as understood herein is that portion of the handle necessary to rotate shaft S and open valve V, and only in a sense comprises grip or sleeve 8, as the actual grip 105 may be exerted mostly on cap 15.

What I claim is:

1. A combined sand and air controller for cars comprising a handle constructed to be rotated from a fixed pivot and having an 110

- axially rotatable part thereon adapted to set in operation a line of mechanism peculiar to itself. 35
2. A handle mechanism for use on cars to control two separate valves, the same comprising a handle member having a sleeve mounted thereon and operatively connected with one of said valves. 40
3. A controller handle for cars consisting of a handle proper having an axially rotatable grip mounted thereon, and a valve and controlling mechanism therefor engaged with said grip and adapted to exert a lifting movement on the valve. 45
4. A controller handle for cars, valves to govern the flow of air for the brakes and sand for the wheels, and mechanism to operate said valves initially connected with said handle and comprising an axially rotatable member and valve lifting parts in one of said lines of mechanism. 50
5. A controller mechanism for cars comprising two valves, a handle having a fixed pivot operatively connected with one of said valves, an axially rotatable sleeve on said handle having a substantially cam shaped projection, and a lift arm for the other valve operated from said cam shaped projection. 55
6. A controller handle for cars comprising a handle stem and a sleeve rotatable thereon having a projection with a substantially V shaped recess in its top, in combination
- with a vertically movable right angled valve controlling member operatively engaged with said recess. 35
7. The handle comprising a stem and a rotatable sleeve thereon having a right angled projection at its end with a substantially cam shaped working portion, in combination with a valve lifting member slidably supported and carrying a roller engaging said cam shaped surface. 40
8. The combination of the handle stem and the head rigid therewith having a hub at its outer extremity and a post at its inner portion, a right angled lift member mounted slidably on said post and a sleeve on said handle stem operatively connected with said lift member. 45
9. A handle mechanism for car service comprising a handle having a central stem and a sleeve member rotatable thereon, a head fixed on said stem having a hub for supporting the same and a vertically disposed post, in combination with a right angled part 55 slidably mounted on said post and having a lateral projection operatively engaged by said sleeve member.

In testimony whereof I sign this specification in the presence of two witnesses.

CLAUDE SPICER.
